UNITED STATES PATENT OFFICE.

RICHARD T. SCHOLES, OF HINSDALE, ILLINOIS.

RAIL ANCHOR.

Original application filed January 3, 1926, Serial No. 79,999. Divided and this application filed April 16, 1926. Serial No. 102,375.

This invention relates to rail anchoring devices, adapted to prevent the creep of the rail when in service. On railroad tracks where the traffic in general moves always in one direction, substantially all of the tendency to creep will be in this one direction and so-called one-way anchors are used adapted to transmit this thrust to the ties and road-bed. In some trackways, due to the passage of 10 trains in both directions, or other causes, the track tends to creep alternately, first in one direction and then in the other, and so-called two-way anchors must be used.

In my copending application Serial No. 15 79,999, filed January 3, 1926, of which this present application is a division, I have disclosed an improved rail-gripping member adapted to be used interchangeably as a part of either a one-way or a two-way rail 20 anchor. This gripping member, and the two-way anchors of which it forms a part, are claimed in said copending parent application, the present divisional application being intended to cover the improved one-way rail anchor, to be used on tracks where the traffic moves usually in one direction only.

The general object of the present invention is to provide an improved one-way rail anchor of the type hereinafter disclosed in 30 detail.

Another object is to provide a simple spring anchor member capable of being quickly and easily applied to the rail base, and gripping the rail with a constant spring 35 pressure.

Another object is to provide an improved applying tool or hook for positioning the rail-gripping member on the rail.

Another object is to provide an anchor 40 comprising two members, one of which grips the rail, and the other being permanently secured to a tie, the two members engaging one another to prevent relative horizontal movement in one direction, but each being 45 capable of vertical movement independently of the other.

Another object is to provide a rail anchor member adapted to distribute the thrust from the rail gripping member to a tie and 50 tie-plate, without permitting the rail gripping member to come in actual engagement with the tie.

Another object is to provide a rail anchor 55 comprising two cooperating members secured to the tie and rail, respectively, whereby the

rail and rail-gripping member may be removed without disturbing the tie-engaging member.

Other objects and advantages of this invention will be apparent from the following 60 detailed description of certain approved forms of the devices used in carrying out the principles of this invention.

In the accompanying drawings:

Fig. 1 is a plan view of a section of a rail, 65 secured to a tie and tie-plate, with the rail anchor members in place on the rail and tie, respectively.

Fig. 2 is an end elevation of the assembly shown in Fig. 1. 70

Fig. 3 is a side elevation of one of the rail-gripping members, and the attaching tools, shown as applied to a rail which is indicated in transverse vertical section.

Fig. 4 is a perspective view of the tie- 75 engaging portion of the rail anchor.

Fig. 5 is an elevation of the attaching hook or tool, this view being taken at right angles to the view of this tool as shown in Fig. 3.

The rail 1 is supported by its base 2 upon the tie-plate 3 carried by the tie 4, the base 2 being held down against the tie-plate and tie by the spikes 5 in the usual manner.

Referring now more particularly to Fig. 3, the rail-gripping portion of the rail anchor is formed of a single-piece metallic bar 6, preferably of substantially square cross-section.

The bar 6 has an intermediate downwardly bowed portion 7 terminating at either end in substantially horizontal portions having surfaces 8 and 9 adapted to bear against the under surface or bottom of the rail base 2 adjacent either edge thereof. One end of the bar is curved upwardly and inwardly, as at 10, to form a hooked end enclosing a notch 11 adapted to fit about one edge of the rail base 2 and bear there-against. There is a small angular clearance at 11 between the upper side of notch 11 and the upper surface of the rail base flange to permit a limited vertical swinging movement of the gripping member about this edge of the rail base when the gripping member is being applied.

The other end of bar 6 is turned upwardly, as at 12, and then inwardly at 13 to enclose a notch 14 adapted to snugly grip the adjacent edge of rail base 2. The two notches 11 and 14 are oppositely disposed and spaced apart a distance substantially equal 100 to 110

to, or slightly less than, the width of the rail base, so that when the member 6 is applied to the rail, the rail base will be snugly gripped between the two upturned ends of this bar 6. The downwardly bowed portion 7 is sufficiently elastic to form a powerful spring which may be flexed sufficiently to permit the application of the member to the rail base, and will subsequently hold the notched ends of the bar firmly in engagement with the opposite rail base flanges. A cam-surface 15 is formed on the inner face of the up-turned end portion 12, extending from the upper edge of notch 14 to the upper surface of the inturned end 13. The undersurface of the upturned end portion 12 is provided with a depression or socket 16, adapted to be engaged by the hooked end 17 of the applying tool, as hereinafter described.

When the member 6 is to be applied to the rail, the end 10 is first hooked from beneath onto one edge of the rail base, so that the notch 11 is engaged with this edge of the rail base flange. This position of the member is indicated in dotted lines in Fig. 3. The hooked end 17 of the applying tool 18 is now inserted in the socket or depression 16, and the tool 18 is of such length that the enlarged head 19 will extend approximately level with the upper surface of the rail 1. An ordinary claw-bar 20, such as is used for removing spikes, is now engaged with the head 19 of the tool 18, and by fulcrumming the bar 20 upon the rail 1, the bar 6 may be drawn up into engagement with the rail base. The spring portion 7 will flex and permit the cam surface 15 to guide the edge of the rail base into engagement with the notch 14. The tool may be conveniently made by forming or welding the hooked end 17 onto the end of an ordinary track spike.

The tie-engaging member (see Figs. 1, 2 and 4) is here shown as an angular metallic bar having a horizontal portion 21, adapted to overlie the top of the tie plate 3, and a vertical portion 22 adapted to bear against one side of the tie 4. Horizontal portion 21 terminates in a downwardly extending spike end 23 adapted to extend through one of the spike holes in the tie plate, and into the tie, and the vertical leg 22 terminates in a horizontal spike 24 adapted to be engaged into the side face of the tie. Intermediate 55, adjacent the upper corner of the tie 4, the anchoring member is bent outwardly to form a lug 25 which bears against the hooked end 10 of the rail-gripping bar 6. At the upper end of vertical leg 22 is an inwardly extending lug 26 adapted to bear against the side edge of tie-plate 3 above the tie 4.

After the member 6 is applied to the rail base 2, it grips the opposite edges of this rail base by the spring pressure furnished

by the downwardly bowed portion 7 with sufficient pressure to resist movement of the member longitudinally of the rail, and prevent any material canting of the member in the plane of the rail base. However, if a pressure is applied lengthwise of the rail to one end of the bar 6, for example, the hooked end 10, there will be a tendency to cant, or a very slight canting of the member in a horizontal plane, which will cause the gripping member to engage the rail base even more firmly and securely lock the gripping member to the rail. This canting movement is so slight that the member will be locked by a force exerted in either direction lengthwise of the rail, without causing any material movement of the gripping member along the rail base. With the parts in position, as shown in Figs. 1 and 2, any creeping of rail 1 toward the right, as shown in these figures, that is so as to bring the gripping member 6 closer to the tie 4, will bring the hooked end 10 of the gripping member 6 into engagement with the outwardly projecting lug 25 of the tie-engaging member, and any further movement of the rail will lock the gripping member 6 firmly in position on the rail base and transmit the thrust through the tie-engaging member to the tie plate 3 and tie 4. At the same time, the up and down or wave motion of rail 1, as the trains pass thereover, will be permitted without causing any corresponding movement of the tie-engaging member, since the gripping member 6 merely bears freely against the lug 25. The rail 1, or the gripping member 6, or both of them, may be removed and replaced without necessitating any disturbance of the tie-engaging member 21. Thus there are no vertical thrusts tending to loosen the spikes 23 and 24. When the rail 1 is relaid, or a new rail is positioned on the ties, a gripping member 6 can be applied to the rail base directly in line with the lug 25 of the tie-engaging member. This is possible, since the application of the gripping member 6 is performed entirely in a vertical plane without requiring any lateral shifting of this gripping member.

It will be noted that although two parts are used to form this rail anchor, these parts merely abut against one another and there is no necessity for properly mating or fitting these parts, so that no selection is required and either part may be replaced without altering the efficiency of the anchor.

The rail gripping member 6 might be applied to the rail by upward pressure, for example, by fulcrumming a crow bar on a tie or the road-bed and lifting up on the under surface of member 6 until the notched end 14 snaps into place on the rail base. However, the use of the applying tool 18 in co-operation with a clawbar fulcrummed on the

rail head is preferable, since in this operation all thrusts are toward the rail, and there is no tendency to loosen spikes or otherwise disturb the anchorage for the rail.

5 It will be noted that there is no direct contact of any portion of the rail-gripping member 6 with the tie. All of the thrust from the rail and rail-anchor is transmitted to the tie through the member 21 which is 10 rigidly and immovably fixed to the tie. In prior forms of rail-anchors, where some portion of the anchor bears directly against the tie, there is a constant wear on the wooden tie caused by the up and down movement of 15 the rail and anchor as the loads pass there-over. In this improved form of anchor, all of this relative movement takes place be-tween the gripping member 6 and the lug 25 on the tie-engaging member 21 and there 20 is no tendency to wear away the tie.

I claim:

1. A rail anchor comprising a member adapted to grip opposite edges of the rail base with a spring pressure, and a member 25 shaped to engage the top and one side of a tie, and having an outstanding lug to be engaged by one projecting end of the rail-gripping member beyond the side of the rail base.

30 2. A rail anchor comprising a member adapted to grip the rail base, and an angular member having spike ends to engage the top and one side of a tie, and an intermediate portion to engage one end of the rail-gripping member.

35 3. In combination with a rail, a tie and a tie-plate mounted between the rail base and the tie, a rail-anchor comprising a member gripping the rail-base at one side of and spaced from the tie, and a member anchored to the tie-plate and tie and having an outwardly projecting portion engaging one end of the first member.

40 4. In a rail anchor, in combination with a member adapted to be secured to the rail, an abutment member comprising a horizontal portion to be secured to a tie-plate and a vertical leg to bear against the side of the tie.

45 5. In a rail anchor, in combination with a member adapted to be secured to the rail, an abutment member comprising a horizontal portion adapted to overlie a tie-plate, and having a downturned spike end to be engaged through a spike hole in the plate and into the tie, and a vertical leg to bear against the side of the tie.

50 6. In a rail anchor, in combination with a member adapted to be secured to the rail,

an abutment member comprising a horizontal portion adapted to overlie a tie-plate, and having a downturned spike end to be engaged through a spike hole in the plate and into the tie, and a vertical leg to bear against the side of the tie, this leg having a horizontally turned spike end to be engaged in the side of the tie.

60 7. In a rail anchor, in combination with a member adapted to be secured to the rail, an abutment member comprising a horizontal portion adapted to overlie a tie-plate, and having a downturned spike end to be engaged through a spike hole in the plate and into the tie, and a vertical leg formed with portions to bear respectively against the sides of the tie and tie-plate.

65 8. In a rail anchor, in combination with a member adapted to be secured to the rail, an abutment member comprising a horizontal portion adapted to overlie a tie-plate, and having a downturned spike end to be engaged through a spike hole in the plate and into the tie, and a vertical leg formed with portions to bear respectively against the sides of the tie and tie-plate and having an inturned spike end to engage in the side of the tie.

70 9. A rail anchor comprising a member adapted to grip the rail base with a spring pressure, and a member adapted to be anchored to a tie and tie-plate and having a portion projecting substantially parallel with the rail and adapted to engage one end of the rail-gripping member.

75 10. A rail anchor comprising a member adapted to grip the rail base with a spring pressure, and a member adapted to be anchored to a tie-plate and bear against one end of the rail-gripping member.

80 11. A rail anchor comprising a member having a downwardly bowed spring portion adapted to extend beneath the rail base and upturned ends notched to grip the edges of the rail base with a spring pressure, in combination with a member adapted to be anchored to a tie-plate and bear against one end of the rail gripping member.

85 12. A rail anchor comprising a member having a downwardly bowed spring portion adapted to extend beneath the rail base and upturned ends notched to grip the edges of the rail base with a spring pressure, in combination with a member adapted to be anchored to a tie and tie-plate and bear against one end of the rail-gripping member.
